UNITED STATES PATENT OFFICE.

JAMES M. ADAMS, OF CHICAGO, ILLINOIS.

SHIP-SALVAGING APPARATUS.

1,404,921.

Specification of Letters Patent. Patented Jan. 31, 1922.

Application filed June 3, 1921. Serial No. 474,814.

To all whom it may concern:

Be it known that I, JAMES M. ADAMS, a citizen of the United States, residing at Chicago, in the county of Cook and State of Illinois, have invented new and useful Improvements in Ship-Salvaging Apparatus, of which the following is a specification.

This invention has relation to a ship and refers particularly to means for discovering the location of a sunken ship. To this end it is my object to provide, on a ship, devices which, when the ship founders, will rise to the surface of the water and remain there as permanent indicators of the location of the ship. A further object is the provision of means, operating in connection with said devices and capable of reaching and attaching themselves to suitable co-operating members of the ship, for raising the ship to the surface.

To this end my invention consists in the various combinations and in the several important features hereinafter fully described and illustrated in the appended drawings of which:

Fig. 1 is an illustration of a sunken ship equipped with the devices of my invention.

Fig. 2 is a fragmentary view of a vessel's hull, showing how my invention is applied to the vessel,

Fig. 3 shows, on a larger scale, portions of the device disclosed in Fig. 2,

Figs. 4 and 5 illustrate the operation of making connection with elements of the invention,

Fig. 6 is a detail view of a certain cable structure necessary for the proper operation of the device, and

Fig. 7 is a complete view disclosing every important element of the structure.

Reference is, in the first instance, invited to Fig. 1, which shows the hull of a vessel resting on the bottom of a body of water, and all of the main features of the invention are embodied in this view. The numeral "1" indicates the hull of a vessel and along the sides of the vessel are provided two series of devices, 2 and 3. The devices on one side being marked 2^a to 2^e, inclusive, and those of the other side 3^a to 3^e, inclusive. From the said devices extend upwardly two corresponding series of light lines 4^a to 4^e, and 5^a to 5^e, inclusive, all of which terminate at the top in suitable floats or buoys, 6^a to 6^e, and 7^a to 7^e, inclusive. On the surface of the water is seen the outline of a

salvaging vessel, 8, and it is noticed that the crew of this vessel has succeeded in making connections with the device, 2^a, for the purpose of raising the sunken ship, as will hereinafter be fully explained.

No attempt is made to describe the type of salvage vessel used, or the number of such vessels required for raising a particular ship, and the outline of the vessel, 8, is only introduced in order to demonstrate the operation of the structures of my invention. The lines 4 and 5 are substantially of even length and this is of importance, because, due to this fact, it is possible to determine whether the ship is resting in its natural position or whether it has turned over on its side in foundering. If the vessel is still in its natural position it is evident that when the lines, 4 and 5, are hauled in by the salvaging vessels, the crews of said vessels can measure the length of the rope ends above the water and, finding them of the same length, can be certain that the ship is on her keel. If the ship has turned in foundering, however, as indicated in Fig. 1, it is noticed that the rope ends extending from one side of the ship will be much longer than those from the other side of the ship and the salvaging crews will then commence to haul in on the short lines until all lines become of even length, whereupon they will know that the ship is now in the proper position to be raised.

The devices 2 and 3, and the method of mounting such devices on a ship are best shown in Figs. 2 and 3, in which I have confined myself to the description of one of these devices but wish it understood that all of the devices are substantially alike. Fig. 2 is a cross sectional view of one side of the vessel, taken amidship, showing one of the ribs, 10, extending from above the deck 1^a, downward to the keel 1^b. One of the devices, 2^a, is shown resting on the deck adjacent to said rib, 10, and it comprises a cylindrical hook, or spear, 11, through which the line 4 is threaded. The top of the line is clamped to the floating member, 6^a, and the bottom of said line is broken off in Fig. 3, but as in Fig. 2 shown to extend through the rib 10, and into a compartment 10^a, at the bottom of which it is fastened. At a certain distance from the bottom the line is made with an enlargement, or core 12, the importance of which will appear presently. Strongly secured to the keel 1^b, is one or

more cables 13, 14, which also extend through the rib 10 and to the spear 11, the bottom of which is shaped to receive said cables and retain them securely fastened. 5 The lower end of the spear is surrounded by a suitable floating member 15, and this float is provided for the purpose of placing and maintaining the structure in a vertical position in the water the moment the ship 10 sinks below the surface.

The operation of my device, so far as it has hereinbefore described, is as follows:

The moment the vessel sinks below the surface it is found that the buoys 6 and 7 15 will remain on the surface and that the floats 15 will operate to swing the spears 11 into a vertical position. In the drawings these spears are shown freely resting on the top of the deck of a ship and it is required 20 that they be allowed sufficient freedom to function properly, but it is, of course, necessary to confine them within some kind of a frame in order to maintain them in this position when the vessel rolls in a heavy 25 sea. The ship continues to sink and the buoys tend to remain afloat, and the result is that the lines 4 and 5 commence to slide through the spears 11, through which they 30 will continue to pass until the vessel reaches the bottom. How much rope is required is 35 of course a question that will have to be determined in each individual case, but I have found through investigation, that most ships founder in less than 500 feet of water and for this reason I am of the opinion 40 that about 500 feet of line is sufficient for each buoy. If 500 foot lines are used and the ship settles at a depth of less than 500 feet and, if the water is in motion, as it 45 usually is, due to tides or river currents, it is most likely that the buoys will be carried along by the current as indicated in Fig. 1 until all of the line is played out. This condition is illustrated in Fig. 3 and 50 it is noticed that the core 12, has entered the passage through the spear 11, and has come to a stop at a shoulder portion 11^a, of this passage.

In Fig. 6 I have illustrated a method 55 of weaving the solid body or core 12 into the line 4. But I wish it understood that it may be embodied in the line in any other suitable manner, so long as it performs its function properly.

55 I am well aware that the lines in the course of time may become somewhat entangled and I do not mean to assert that it will not take some time to disentangle these lines, but I have found that when the buoys 60 are prominently numbered or otherwise marked to indicate the position they take on the ship, such as No. 1 aft, No. 2 aft, No. 3 midship, No. 2 fore, No. 1 fore, or some similar system of marking, it will not 65 be very difficult to separate the various lines.

The salvage vessels are required to carry suitable devices for engagement with the spears 11, and such devices may take the shape indicated in Fig. 4. When a buoy is hauled in by the crew, it is detached from 70 its line, and the end of the line is inserted through a cylindrical body 18, which latter in turn is attached to the ends of a plurality of strong cables 20 and 21. The lower extremity of the body 18 is provided with a 75 pair of spring-held jaws 17 and 18, which take a position facing each other. The end of the buoy line is now securely fastened on the salvaging vessel, and the body 18 is then permitted to slide downward along 80 said lines until the jaws 17 and 18 slide over the head portion 11^b, of the spear 11, and engage a shoulder 11^c directly below this head portion. The sunken ship is now, at least so far as these particular cable and 85 gripping devices is concerned, ready to be raised, and this position is indicated at 2^a and 4^a in Fig. 1. The cables 20 and 21 are here shown bent over a boom 23, such as usually employed in apparatus of this 90 kind, but it may of course be operated upon in any other suitable manner.

It is my plan to confine myself, if possible, to one standard size of apparatus, having the cables, the spears and gripper jaws of 95 one uniform size. Ships that ply the rivers and seas of the world, vary, of course, a great deal in size, and as a consequence the cables, the spears and grippers units, which it will be necessary to install on each individual vessel, will vary accordingly in 100 number, but as stated, each unit will be of the same size.

The details of the gripping mechanism are best shown in Fig. 5, in which the jaws 105 17 and 18 are pivotally hung on the body 18 by suitable studs 24 and 25 and they are urged together by resilient members 26 and 27. It is noticed that the body 18 is made with a plurality of passages 18^a and 18^b, 110 in which the hauling cables 20 and 21 are seated. I prefer, however, to employ only one cable and to thread the end of this cable through the passage 18^a, whereupon 115 the cable is caused to make several turns along the reduced portion or neck 18^c of the body, and it is then returned through the second passage 18^b. This I have found to be a very substantial way of attaching 120 the cable where the two strands 20 and 21 are used. It is of course necessary where more than two strands are employed to fasten the ends of the cables to the gripper body in some other suitable manner. The means of fastening the anchor cable in the 125 spear 11 may conveniently be substantially the same as just described in connection with the grippers. Such construction is indicated in Fig. 3.

The ribs 10, through which the buoy line 130

and anchor cable extend must, of course, be especially designed for the hereinbefore stated purpose, and they must be made strong enough to carry the proportion of the 5 weight assigned to each gripper device.

It was above stated that the cables 13, 14 extended through the rib 10 and to the keel of the vessel. I may, however, secure these 10 cables to the top of the ribs, in any suitable manner, and then depend upon the ribs alone to carry the weight of the vessel, in which case the ribs might have to be made stronger, but perhaps not so expensive.

In Fig. 1 I showed the spears 11 mounted 15 close to the top of the said ribs, and the spears did, as will be remembered, form part of the devices 2^a to 2^b and 3^a to 3^b, but it may be of advantage to carry these structures further away from the ribs, as indicated in Fig. 7. In this view the sunken 20 vessel is shown on its keel, and the devices 30^a to 30^b, inclusive, are placed far enough from the ribs, by using longer cables 31, 32, to clear the vessel, even when the vessel has 25 turned on its side, as shown in Fig. 1. The moment the vessel settles on the bottom it is found that sand commences to gather around the hull, and such gathering sand may soon cover the devices 3^a, 3^b, of Fig. 1. 30 But when the longer cables 31, 32 are employed it is found that all the said devices will rise clear of the hull, if the cables are longer than the width of the vessel.

Further modifications may suggest themselves, and I reserve the privilege to embody such modifications so long as they come within the scope of my invention.

I claim:

1. In a device of the character described, 40 a series of members anchored in the hull of a vessel, means urging said members into a vertical position when the vessel is submerged, a corresponding series of buoys, and buoy lines extending from the hull and 45 through said members to said buoys.

2. In a ship salvaging device, a plurality 50 of clutch members anchored to the hull of a ship by flexible cables and capable of seeking a vertical position when the vessel sinks below the surface, buoy lines extending from the vessel and through said members, and a buoy attached to the end of each line, and means provided with jaws and mountable and slidable on said lines for engagement 55 with said members, for the purpose specified.

3. In a ship salvaging device, a plurality 60 of spear shaped members anchored to the vessel by flexible cables longer than the width of the vessel, lines extending from the vessel and passing through said members, floats to which the ends of said lines are attached, and an enlarged portion on each line and shaped to engage a shoulder portion in 65 the passage through said members, for the

purpose of anchoring the lines in the members, when said lines are fully played out.

4. In a device of the character described, a plurality of clutch members anchored to a vessel by flexible devices, floats attached 70 to said members for the purpose of turning said members into a vertical position the moment the vessel sinks below the surface, means extending from said members for indicating the location of said vessel and members, and means applicable to said locating means for engagement with said members for the purpose of raising the vessel.

5. In a salvaging device, clutch members anchored in a ship, means urging said members into a vertical position when the ship is submerged, buoy carrying lines passing through said members, and means applicable to said lines and slidable on the lines for engaging said members to raise the vessel.

6. In a salvaging device, the combination with a vessel having channeled ribs extending from railing to keel, of anchoring cables secured to said keel and extending through 90 said channels, clutch members attached to the free end of said cables, locating means extending from said members, and salvaging devices applicable to said locating means for engaging said members.

7. In a salvaging apparatus, the combination with a vessel having a plurality of channeled ribs extending from railing to keel, of a plurality of clutch members, flexible elements extending from the keel 100 through said channeled ribs for anchoring said members to the vessel, means urging said members into a vertical position in the water, buoy lines coiled at the bottom of said ribs and extending through the members, buoys attachable to the ends of the lines, and means applicable to and slidable on said lines for engaging said members to raise the vessel.

8. In a ship salvaging device, a plurality 110 of spear-shaped members, each having a central passage and made with an enlarged lower portion having two additional passages, a cable extending from the ship and through one of the latter passages, thence 115 wound around the spear above said enlarged portion and returned through the other passage to the keel, a buoy line extending from the ship and through said central passage, and means slidable on said line for engaging said spear to raise the vessel.

9. In a salvaging apparatus, a plurality 125 of clutch members anchored in a vessel by means of flexible cables longer than the width of the vessel and extending a uniform distance above the deck of the vessel, buoy lines extending from the vessel and through said members, buoys attached to the ends of said lines and causing the lines to slide through the members as the ship sinks, and 130

enlargements on said lines and engaging a shoulder portion in the passage through said members, whereby said buoys are held anchored a uniform distance from said members.

10. In a salvaging apparatus, a plurality of clutch members anchored in a vessel by flexible devices and capable of seeking an upright position when the vessel is submerged, buoy lines of uniform length extending from said members, buoys attached to the ends of said lines, said buoys being marked or numbered relative to their position on the vessel, and means applicable to said lines for engaging said members.

11. In a salvaging device, a plurality of clutch members anchored in a vessel by means of flexible cables, means on said members seeking to maintain the members in a vertical position when the vessel is submerged, lines coiled at the bottom of the vessel and passing through ribs of the vessel and then through said members, said lines having enlargements for engagement with a shoulder portion in the passage through said members, and marked floats attached to the ends of said lines a uniform distance from said enlargements.

12. In a device of the character described, clutch members anchored in a vessel, buoy lines extending through said members to the surface, clutch members anchored in salvaging vessels for engagement with the first named members and slideable on said lines, all of said members having head portions shaped for interengagement, provided with

a contracted intermediate portion and an enlarged tail-portion, said tail provided with longitudinal perforations through which the anchoring cables pass, said cables being wound around the said intermediate portion.

13. A buoyant tubular spear anchored in a ship by cables longer than the width of the ship, a buoy line extending from the ship through said spear and having an enlargement intermediate its ends, said enlargement capable of entering the spear but arrested by a shoulder in the passage through the spear, and means slideable from above down the buoy line and capable of engaging said spear.

14. In a ship salvaging apparatus, a series of tubular spears anchored in a ship by cables extendable from the ship further than the width of the ship, a buoy line anchored in the ship for each spear and extending through each spear, said line having an enlargement intermediate its ends, which enlargement is of a size to enter the passage through the spear but arrested by a shoulder portion of the passage, for the reason of which the spear may be drawn free and clear of the sunken vessel from above, a buoy on the end of said line for locating the line, and clutching means slideable down said line for engagement with said spear.

In testimony whereof I have hereunto affixed my signature.

JAMES M. ADAMS.
